UNITED STATES PATENT OFFICE.

ROBERT L. DEAN, OF KANSAS CITY, MISSOURI, ASSIGNOR, BY MESNE ASSIGNMENTS, TO DEAN RAPID TELEGRAPH CO., A CORPORATION OF ARIZONA TERRITORY.

SYSTEM OF TELEGRAPHY.

No. 920,833.

Specification of Letters Patent.

Patented May 4, 1909.

Application filed April 5, 1906. Serial No. 309,985.

To all whom it may concern:

Be it known that I, ROBERT L. DEAN, a citizen of the United States, residing at Kansas City, in the county of Jackson and State of Missouri, have invented certain new and useful Improvements in Systems of Telegraphy, of which the following is a specification.

My invention relates to the transmission and recording of electrical impulses for telegraph purposes in which the transmission is automatically accomplished through the aid of perforated sheets, and wherein the messages are printed in page form.

The system embraces a transmitter which feeds the perforated sheets forwardly step by step; a reciprocating contact device, forming part of the transmitter, which is drawn over the successive rows of character-holes in the sheets when the latter pause between each forward step; a receiver for feeding the paper to be printed upon, forwardly step by step as successive lines are printed thereon; a reciprocating recording device in the receiver for printing a row of characters upon the paper at each pause of the latter between steps, and means for synchronizing the movements of the contact and recording devices and the feed mechanisms of the transmitter and receiver.

The invention also embraces an alphabet or code containing twenty-six characters and a punctuating mark, any one of which may be printed by two type on the recording device. As most of the characters may be printed by two impulses the time required to prepare a perforated sheet for a telegram and to transmit the latter is brief, and the consumption of battery power is reduced to a minimum.

In practice each station is equipped with a transmitter and a receiver, the transmitter at one station being in circuit with the receiver at the other station, and for convenience and economy the two instruments at each station may be coupled to a single motor. While it is desirable to have motors which travel at the same rate of speed this is not an absolute necessity as the synchronizing mechanism will cause the receiver at one station, to operate in proper time with the transmitter at the other station.

Referring now to the accompanying drawings which illustrate the invention:—Figure 1 represents a plan view of the transmitter.

Fig. 2 is a vertical transverse section of same, taken on line II—II of Fig. 1. Fig. 3 is a broken transverse section on line III—III of Fig. 1. Fig. 4 is a broken side elevation of the upper portion of the transmitter locking in the same direction as Fig. 3. Fig. 5 is a side elevation of the contact device forming part of the transmitter. Fig. 6 is a broken horizontal section of same taken on line VI—VI of Fig. 5. Fig. 7 is a detail perspective view of the contact device. Fig. 8 is a vertical transverse section of the receiver, taken on a line corresponding to II—II of Fig. 1. Fig. 9 is a side elevation of the recording device. Fig. 10 is a broken inverted plan view of the same. Fig. 11 represents a diagram of two stations equipped with my apparatus which is connected for transmitting and receiving messages. Fig. 12 shows the alphabet in perforated characters, together with the characters of my alphabet and the letters and punctuation mark which they represent.

The apparatus of this invention is, preferably, arranged for actual work as shown in Fig. 11 so that a single line wire may be used to transmit and receive telegrams, and in order that it may be fully understood I will now proceed with a detailed description of said apparatus, the transmitter being first described. The frame of said transmitter comprises a base-plate 1, end-plates 2 mounted thereon and tie-rods 3 uniting the upper portions of said end-plates.

4 designates a table located in the front portion of the frame to support the perforated sheet 5 which passes over two conductors 6 7 separated by an insulating strip 8 extending the entire length thereof. Sheet 5 is provided with rows of character-holes 5^a, said rows being arranged in pairs with the character-holes of one row arranged with respect to those in the companion row, as shown, so that one roller of the contact device, hereinafter described, will not enter a perforation in one row until its companion roller leaves a perforation in the other row. Thus short circuiting, which would prevent the transmission of proper impulses to the receiver, will be obviated. Said contact device consists of a cross-head 9 of nonconducting material, a plate 10 secured thereon and provided with stops 11, a shifting-nut 12 provided with lugs 13 and slidably arranged in the stops, a shifting-lever 14 for operating the shifting-nut, and a pair of arms 15 16 110

carrying antifriction contact rollers 17 18 normally held in a depressed condition by tension-springs 19 attached to the rear ends of the arms and screw-eyes arranged in a bracket 20, to which latter arms 15 16 are pivotally secured. Nut 12 is provided with depending pins 21 and a centrally disposed slot 22 through which latter a screw 23 extends and enters plate 10. Lever 14 is fulcrumed upon and oscillates on said screw and is provided with a pair of eccentric shoulders 24 and straight shoulders 25, the former of which alternately engage the pins and thus shift the nut in opposite directions while the latter also alternately engage the pins and thus prevent accidental movement of the nut when the shifting-lever is at rest, see Fig. 6. The oscillatory movement of the lever is controlled by actuating mechanism hereinafter described and its movement is limited by its arms 26 27 striking stops 11. The contact device carries a push-bar 28 which aids in synchronizing the movements of the transmitter and the receiver as will hereinafter appear. Said push-bar extends loosely through the cross-head and is held therein by a coil-spring 29 secured at its ends to the cross-head and a collar 30 fixed to one end of the push-bar.

Cross-head 9 is reciprocably mounted upon a pair of guide-rods 31 32 secured at their ends to insulating blocks 33 34, fastened to the inner sides of the end-plates 2 and supporting the conductors 6 and 7. Said blocks also carry circuit-breakers A and B, respectively, forming part of the synchronizer. Each circuit-breaker consists of a bell-crank lever 35 and a contact-point 36, the former of which is normally held away from the latter by its weighted end 37. Levers 35 are pivotally secured to lugs 35^a and arranged in the path of push-bar 28 so that the latter will alternately contact therewith and thus close said circuit-breakers.

The contact device is moved to and fro over the perforated sheet by a pair of worms 38 39 journaled in the end-plates. Worm 38 is provided at its ends with fixed friction-wheels 40 41 the former of which is driven by a friction-wheel 42 on a motor shaft 43 while the latter engages and drives, in a reverse direction, a friction-wheel 44 fixed to one end of worm 39. The terminals of the worm threads are arranged out of alignment with each other, as shown in Fig. 1, so that the nut will pass out of engagement with one thread before it engages the opposing thread. Said nut is actuated upon reaching the end of its right and left strokes by arms 45 46, respectively, pivotally secured to blocks 33 34. Said arms are operated by a solenoid 47 which is actuated by electrical impulses timed by the synchronizer, as hereinafter described. The plunger 48 of the solenoid 45 is pivotally secured to a connecting-bar 49

which in turn is pivotally secured to one arm of an irregular-shaped lever 50 fixed to a rocker-shaft 51 mounted in the end-plates 2. The upper end of lever 50 is secured to arm 45 by a connecting-bar 52, and its lower terminal is provided with a pawl 53, pivotally secured thereto, for actuating a pair of feed-rollers 55 56 whereby the perforated sheet is fed through the transmitter. In order that the perforated sheet may move forward step by step without interference from rollers 17 18, the same are raised from contact with said sheet by their outwardly-projecting spindles 18^a alternately traveling upon inclined arms 18^b 18^c extending from blocks 33 34, respectively. Roller 55 is provided at its opposite ends with reversely-disposed ratchet-wheels 57 58, respectively, the former of which is engaged by pawl 53 whereby it is moved the distance of one tooth each time the solenoid is energized. The teeth of ratchet-wheel 57 are spaced to correspond with the rows of character-holes 5^a so that each time the perforated sheet is moved forwardly a succeeding pair of rows will be brought into position upon conductors 6 and 7 and beneath the contact rollers 17 and 18. The lengths of the steps are equalized by ratchet-wheel 58 and a detent 59, which latter is pivotally secured to the adjacent end-plate and provided with a shoulder 60 which is thrown into engagement with the ratchet-wheel by a tension-spring 61 when the free end of the detent is tripped. Said detent is normally supported above its ratchet-wheel by a pin 62 projecting laterally from the lower end of a trip-lever 63 fixed to rocker-shaft 51 so that the action of said trip-lever and lever 50 will be synchronous. Lever 63 is secured to arm 46 by a connecting-bar 64. Thus when the feed-roller is turned by pawl 53 the detent will be tripped so that its shoulder 60 will engage ratchet-wheel 58 and intercept its following tooth. After the actuating mechanism has turned the feed-rollers one-step and the solenoid has become deenergized, said actuating mechanism is returned to normal by means of a retractile spring 51^a and a crank-arm 51^b which latter is fixed to one end of rocker-shaft 51. The movements of crank-arm 51^b are limited by stop-pins 51^c. The perforated sheet 5 is held in frictional contact with feed-roller 55, so that it will not slip thereon, by the feed-roller 56 which is journaled in bell-crank bearings 65 pivotally secured to the side plates by screws 66. The free ends of bearings 65 are held in a depressed position by a bow-spring 67, the tension of which is regulated by an adjusting-screw 68 extending through an internally-threaded rod 69 secured in the end-plates. One end of the shaft carrying feed-rollers 55 extends through one of the end-plates and is provided with a hand-wheel 70 whereby said

feed-roller is turned to start the front edge of the perforated sheet between the feed-rollers.

The construction and operation of the receiver is similar to that of the transmitter, but in order that its co-operation with the latter may be fully understood I will now refer thereto in detail. The frame of said receiver consists of a base-plate 71, end plates 72 mounted thereon, and tie-rods 73 10 uniting the upper portions of said plates.

74 designates a roll of paper mounted upon a shaft 75 journaled in brackets 76 secured to the end plates. One end of said roll is passed between a pair of distributing-rollers 77 78 and a pair of feed-rollers 79 80, the movements of which latter are synchronous with those of rollers 55 56. In its passage between rollers 77 78 the paper is treated with a chemical solution in order that the 20 messages may be printed thereon, the solution employed for this purpose being contained in a receptacle 81 from which it is carried to the paper by roller 77 which has its lower portion submerged therein. The 25 solution is evenly distributed throughout the paper and all surplus is expressed therefrom by rollers 77 78, which latter is held downwardly upon the paper by a bow-spring 82 pressing downwardly upon its bearing 83 pivotally secured to the end-plates by screws 84. The tension of spring 82 is regulated by an adjusting-screw 85 extending through an internally-threaded rod 86 secured to the end plates. The paper is 30 held in frictional contact with roller 79, so that it will move therewith, by roller 80 which is pressed downwardly upon said paper by a bow-spring 87 engaging its bearings 88 which are pivotally secured to the 35 end plates by screws 89. The tension of screw 87 is regulated by an adjusting-screw 90 extending through an internally-threaded rod 91 secured to the end plates. Roller 79 is turned step by step through the 40 instrumentality of a fixed ratchet-wheel 92 and a pawl 93 engaging said ratchet-wheel. Pawl 93 is pivotally secured to an irregular-shaped lever 94 fixed upon a rocker-shaft 95 and actuated by a solenoid 96 provided with a 45 plunger 97 secured to the irregular-shaped lever by a connecting-rod 98. Lever 94 is also connected to and operates an arm 99 through a connecting-rod 100. Arm 99 is 50 pivotally secured to an insulating block 101 which also supports the adjacent ends of conductors 102 103, the opposite ends of which latter are secured to another insulating block 105. The movements of roller 79 are limited by mechanism similar to that 55 employed for limiting and equalizing the steps taken by roller 55.

104 designates a platen over which the paper travels after leaving the distributing-rollers, the ends of said platen being secured 60 to the undersides of blocks 101 105, both of

which are secured to the end-plates 72. Said blocks are provided with circuit breakers C D connected to circuit breakers A B, respectively, and forming part of the synchronizer. Circuit-breakers C D consist of contact points 106 and bell-crank levers 107 which latter are pivoted to lugs 108 secured to the insulating blocks. Levers 107 are normally held away from contact points 106 by their weighted ends 109. Levers 107 are 70 arranged in the path of a push-bar 110 loosely mounted in the cross-head 111 of a recording device consisting of said cross-head, a pair of character bearing arms 112 113, pivotally secured to a bracket 115 on 80 the cross-head. The underside of arms 112 113 are provided at their free ends with characters 116 117, respectively, which co-operate in printing certain letters of my alphabet on the chemically treated paper, 85 upon which latter they are held by spring-pressed pins 118. Character 117, is, however, so formed that it will print the letters A, H, I, M, R and T without the aid of character 116. Character 116 consists of 90 a transverse bar which prints a portion of the transverse elements of a number of the letters. Character 117 consists of a bar 117^a, for printing the vertical elements of the letters, and transverse bars 117^b for printing 95 the remainder of the transverse elements of the letters. Push-bar 110 is held in its normal position by a coil-spring 119 secured at its ends to the cross-head and a collar 120 fixed to said push-bar. Cross-head 111 is 100 reciprocably mounted upon conductors 102 103 and provided with a plate 121 having stops 122 for limiting the movement of a shifting-lever 123 fulcrumed upon a screw 124, upon which is slidably mounted, between 105 the stops, a shifting-nut 125 adapted to be alternately thrown by shifting lever 123 into engagement with worms 126 127, journaled in the end plates and rotated in reverse directions by friction-wheels similar to those 110 employed in driving worms 38 39.

In order that the paper 74 may move step by step without interference from characters 116 117, the same are raised from contact with the paper by their arms 112 113 alternately traveling upon the inclined arms 130 131 projecting from blocks 101 105, respectively.

Referring to the diagram, Fig. 11, E designates a station equipped with a transmitter 120 and a receiver arranged in circuit with similar apparatus in station F. In practice the motors for operating the apparatus, are, preferably, arranged to travel at the same rate of speed although this is not absolutely 125 necessary because the synchronizer, consisting of the circuit-breakers and push-bars, will keep the apparatus in one station properly timed with that in the other station, as will hereinafter appear. Should the operator at 130

station E desire to forward a message to station F he places a perforated sheet 5 in position in the transmitter. Communication is then established over the line wire G by 5 throwing switches H I to the positions shown and closing key J. As the circuit-breakers B and C are normally held in a closed position by push-bars 28 110, respectively, the closing of said key will establish a circuit through a main battery K, a relay L, a circuit-wire M, the circuit-breaker B, a circuit-wire N, line wire G, a circuit-wire O; a relay P; a circuit-wire Q, the circuit-breaker C, a circuit-wire R to ground, and thence back to battery K, 10 through a line wire S and a branch-wire T. The establishment of this circuit will energize the relay magnets and cause them to draw their armatures l and p against contact-points l' and p', respectively, and thus close two local circuits U V, comprising batteries W W' and circuit-wires X X'. As the solenoids 47, 96, are in circuit with wires X X'; respectively, the closing of the local circuits will energize said solenoids and cause them to 15 draw their plungers downwardly and thus turn the respective feed-rollers of the transmitter and the receiver one step. This action of the transmitter feed-rollers will move sheet 5 forward so that its first pair of perforated rows will be brought between the contact device and conductors 6 7. The action of the plungers will also throw arms 46 99^a into contact with shifting-levers 14, 123, respectively, which in turn throw their 20 respective shifting-nuts into engagement with worms 38 126, so that said worms will move the contact and recording devices to the right. As the contact and recording devices move to the right their push-bars will 25 be drawn away from the circuit-breakers B C so they may resume their normal positions and interrupt the local circuits just described. When the contact roller 17 enters the character-holes of its respective row of perforations it will successively contact with conductor 7 and send impulses corresponding in 30 length to said character-holes, to character 117 over a circuit consisting of battery K, a circuit-wire Y, conductor 7, roller 17, arm 15, circuit-wire a, guide-rod 31, circuit-wire N, line wire G, wire O; conductor 102^a, circuit-wire b, arm 113, character 117, platen 104, character 116, arm 112, conductor 103, wire R to ground, and then return to battery 35 K through wires S and T. When roller 18 enters a character-hole in its respective row the current will be reversed and pass over a circuit consisting of a main battery K', branch-wire T, and circuit-wire S to ground, thence to line-wire R, conductor 103, a circuit-wire c, arm 112, character 116, platen 104, character 117, wire b, conductor 102, wire O; line wire G, wire N, conductor 31, wire a, arm 16, roller 18, conductor 6, and 40 thence return to battery K', through a circuit-wire b'. As the impulses pass through characters 116 117, the latter act like positive and negative poles and print the proper characters upon the paper. For instance, when an impulse goes direct to character 116 the latter will print upon the paper, and when an impulse is transmitted to character 117 the latter will print upon said paper. Thus as the contact device moves across sheet 5 the recording device will move across paper 45 74, printing characters thereon as pre-determined by the character holes 5^a. Should the contact device reach the end of a stroke, for instance a right stroke, before the recording device, push-bar 28 will close circuit-breaker A and hold it in this position until push-bar 110 closes circuit-breaker D. The closing of said circuit-breakers establishes a current over the main line through battery K, which current will close the relays and 50 cause the latter to close the local circuits U V, causing the solenoids to throw arms 45 99 into contact with shifting-levers 14 123, respectively, which in turn throw their respective shifting-nuts into engagement with worms 39 127 whereby the contact and registering devices will be returned to the left side of their respective machines. While arms 45 99 are being thrown into contact with the shifting-levers, the feed-rollers on 55 the transmitter and receiver are simultaneously turned one step by the downward movements of plungers 48 97 and thus move sheet 5 and paper 75 forward one step.

From the foregoing description it will be 100 understood that the contact and recording devices will be made to start together on each stroke through the action of the push-bars and the circuit-breakers. After the message has been printed key J is thrown 105 open, and should this latter operation occur while the contact and recording devices are moving to the right, the main line and local circuits will be established when circuit-breakers A D are closed by the push-bars, 110 hence the shifting-nuts 12 125 will be thrown into engagement with worms 39 127 and thereby be returned to the end of their left stroke. When the contact and recording devices reach this last position their push-bars will close circuit-breakers B C, but as 115 communication between relay L and circuit-breaker B has been interrupted by opening the key said relay will not act, hence the circuits will remain broken, and the contact and recording devices will remain in the last-mentioned position until the key is closed. Thus said devices will always be 120 ready to transmit and receive another message.

In Fig. 12 I have shown my alphabet consisting of twenty-six letters and a period. A number of these letters are printed by the character 117 while the remainder are printed by said character and character 116. These 130

characters are assisted in forming the letters by a predetermined number of character-holes 5^a, of variable lengths, the spaces between said holes, and the position the holes 5 in the upper row occupy with respect to those in its companion row. For instance, when printing the letter A two short impulses with but a slight intervening pause will be transmitted through the contact roller 10 17 to character 117. When printing the letter D one long and one short impulse will be transmitted through roller 17 to character 117 and one short impulse will be transmitted through roller 18 to character 116 15 during the pause between the long and short impulse just referred to. By first transmitting a long impulse to character 117, the first vertical element of D will be wider than the second and thus render D easily distinguishable from B in which the reverse condition exists. Thus it will be understood that by employing this alphabet and printing the letters thereof in the manner described, all complicated mechanism, such, for instance, as sunflower apparatus may be dispensed with, and at the same time I obtain separated letters which, owing to their similarity to those of the English alphabet, may be read at sight with but little practice.

30 Having thus described my invention what I claim and desire to secure by Letters-Patent, is:—

1. In a system of telegraphy, reciprocably mounted arms having characters adapted to engage chemically-treated paper, reciprocably mounted contact arms in circuit with said characters, adapted to alternately enter character-holes in a perforated sheet and temporarily close the circuit, the duration 35 of the impulses thus transmitted to the characters being controlled by the length of the character-holes, mechanisms for moving the perforated sheet and the treated paper forwardly step by step, and means for synchronizing the movements of said mechanisms.

2. In a system of telegraphy, a main circuit, a reciprocably mounted recording device arranged therein and provided with 50 characters adapted to engage the paper to be printed upon, a push-bar carried by said device, circuit-breakers which are alternately closed by said push-bar and arranged in the main circuit, a reciprocably mounted contact device having arms in circuit with the characters and adapted to enter the character-holes of a perforated sheet, a push-bar carried by said contact device, circuit-breakers which are alternately closed by 55 said push-bar and arranged in the main circuit, electromagnets in circuit with the main line and the circuit-breakers so that when two of the latter are closed said magnets will be energized, two local circuits which are 60 synchronously closed by the energized mag-

nets, solenoids which are energized when said local circuits are closed, and feed mechanisms for feeding the paper and the perforated sheet which are synchronously actuated by said solenoids.

3. In a system of telegraphy, reciprocably mounted arms having characters adapted to engage chemically-treated paper, a shifting-nut for reciprocating said arms, reciprocably mounted contact arms in circuit with said characters adapted to enter character-holes in a perforated sheet and temporarily close the circuit, the duration of the impulses thus transmitted to the characters being controlled by the length of the character-holes, 70 a shifting-nut for reciprocating the contact arms, mechanisms for moving the perforated sheet and the treated paper forwardly step by step, inclines for raising the contact arms from the perforated sheet preparatory to advancing the latter, inclines for raising the character-arms from the paper preparatory to advancing the same, and means for preventing accidental movement of the shifting-nuts.

4. In a system of telegraphy, a transmitter consisting of a pair of reversely-driven worms, a contact device adapted to make and break an electric circuit, a shifting-nut carried by said device, members carried by 95 said nut, a shifting-lever having eccentric shoulders and straight shoulders for alternately engaging said members, and means for actuating said shifting-lever so that it will alternately throw the shifting-nut into 100 engagement with the worms.

5. In a system of telegraphy, a transmitter consisting of a pair of reversely-driven worms, a contact device adapted to make and break an electric circuit, a shifting-nut 105 carried by said device, members carried by said nut, a shifting-lever having eccentric shoulders and straight shoulders for alternately engaging said members, and solenoids for actuating said shifting-lever so that it 110 will alternately throw the shifting-nut into engagement with the worms.

6. In a system of telegraphy, two reciprocably mounted arms, two characters thereon embracing all of the elements for printing 115 separate letters of an alphabet, chemically treated paper upon which said characters travel, and reciprocably mounted contact arms in circuit with said characters adapted to enter character-holes in a perforated sheet 120 and temporarily close the circuit, the duration of the impulses thus transmitted to the characters being controlled by the length of the character-holes.

7. In a system of telegraphy, two reciprocably mounted arms, two coacting characters thereon containing vertical and transverse elements for printing all of the letters of an alphabet in separate form, two reciprocably mounted contact arms in circuit with said 130

characters and adapted to enter character-holes in a perforated sheet and temporarily close said circuit, conductors arranged beneath said sheet so that the contact arms 5 will engage said conductors one at a time while passing through the character-holes, and independent electrical sources of supply in circuit with said conductors.

8. In a system of telegraphy, two reciprocably mounted arms, two coating characters thereon containing vertical and transverse elements for printing all of the letters of an alphabet in separate form upon chemically-treated paper, reciprocably mounted contact arms in circuit with said characters adapted to enter character-holes in a perforated sheet and temporarily close the circuit, the duration of the impulses thus transmitted to the characters being controlled by the length of 15 the character-holes, and mechanisms for moving the perforated sheet and the treated paper forwardly step by step.

9. In a system of telegraphy, a pair of reciprocably mounted arms, two characters 25 thereon containing vertical and transverse elements for printing all of the letters of an alphabet in separate form upon chemically-treated paper, reciprocably mounted contact arms in circuit with said characters adapted to enter character-holes in a perforated sheet and temporarily close the circuit, the duration of the impulses thus transmitted to the characters being controlled by the length of the 30 character-holes, electrically controlled means 35 for feeding the treated paper forwardly step by step, and similar means for feeding the perforated sheet forwardly step by step.

10. In a system of telegraphy, a pair of reciprocably mounted arms, two characters 40 thereon containing vertical and transverse elements for printing all of the letters of an alphabet in separate form, two reciprocably mounted contact arms in circuit with said characters adapted to enter character-holes 45 in a perforated sheet and temporarily close the circuit, the duration of the impulses thus transmitted to the characters being controlled by the length of the character-holes, and means for synchronizing the movements 50 of the contact and character-bearing arms.

11. In a system of telegraphy, two contact arms reciprocably mounted and arranged to enter character-holes in a perforated sheet, conductors arranged beneath the sheet with 55 which said arms contact on entering the character-holes, independent electrical sources of supply in circuit with said conductors, two arms reciprocably mounted, two characters thereon containing vertical 60 and transverse elements for printing all of the letters of an alphabet in separate form upon chemically-treated paper, circuits connecting said contact and character-bearing arms whereby electrical impulses are transmitted 65 to the latter from sources of supply as the

respective contact arms enter the character-holes, feed rollers for moving the perforated sheet step by step, and feed rollers for moving the chemically-treated paper step by step.

12. In a system of telegraphy, two contact arms reciprocably mounted and arranged to enter character-holes in a perforated sheet, conductors arranged beneath the sheet with which said arms contact on entering the character-holes, independent 70 electrical sources of supply in circuit with said conductors, two arms reciprocably mounted, two characters thereon containing vertical and transverse elements for printing all of the characters of an alphabet in separate form 75 upon chemically-treated paper, said contact and character-bearing arms being connected in such manner that electrical impulses will be transmitted to the latter from the sources of supply as the respective contact arms enter 80 the character-holes, feed-rollers for moving the perforated sheet step by step, feed-rollers for moving the chemically-treated paper step by step, and solenoids for actuating the feed-rollers. 90

13. In a system of telegraphy, contact arms reciprocably mounted and arranged to enter character-holes in a perforated sheet, conductors arranged beneath the sheet with which said arms contact on entering the character-holes, independent electrical sources of supply in circuit with said conductors, two arms reciprocably mounted, two characters thereon containing elements for printing all of the characters of an alphabet 95 in separate form upon chemically-treated paper, said contact and character-bearing arms being connected in such manner that electrical impulses will be transmitted to the latter from the sources of supply as the respective contact arms enter 100 the character-holes, feed-rollers for moving the perforated sheet step by step, feed-rollers for moving the chemically-treated paper step by step, solenoids for actuating the feed-rollers, and 110 means for synchronizing the movements of said solenoids.

14. In a system of telegraphy, two contact arms reciprocably mounted and arranged to enter character-holes in a perforated sheet, conductors arranged beneath the sheet with which said arms contact on entering the character-holes, independent electrical sources of supply in circuit with said conductors, two arms reciprocably mounted, two characters thereon containing elements for printing all of the characters of an alphabet 115 in separate form upon paper, said contact and character-bearing arms being connected in such manner that electrical impulses will be transmitted to the latter from the sources of supply as their respective contact arms enter the character-holes, feed-rollers for moving the perforated sheet step by step, means for equalizing said steps, feed-rollers 120 125 130

for moving the paper to be printed upon step by step, and means for equalizing said steps.

15. In a system of telegraphy, two reciprocably mounted arms, two characters on said arms containing vertical and transverse elements for printing all of the letters of an alphabet, chemically-treated paper upon which said characters travel, reciprocably mounted contact arms in circuit with said characters and adapted to enter character-holes in a perforated sheet and temporarily close the circuit, the duration of the impulses thus transmitted to the characters being controlled by the length of the character-holes, 10 mechanisms for moving the perforated sheet and the treated paper forwardly step by step, means for raising the contact arms from the perforated sheet preparatory to advancing the latter, and means for raising the character-arms from the paper preparatory to advancing the same.

16. In a system of telegraphy, two reciprocably mounted arms, two characters on said arms containing vertical and transverse elements for printing all of the letters of an alphabet, chemically-treated paper upon which said characters travel, reciprocably mounted contact arms in circuit with said characters and adapted to enter character-holes in a perforated sheet and temporarily close the circuit, the duration of the impulses thus transmitted to the characters being controlled by the length of the character-holes, 25 mechanisms for moving the perforated sheet and the treated paper forwardly step by step, inclines for raising the contact arms from the perforated sheet preparatory to advancing the latter, and inclines for raising the character-arms from the paper preparatory to 30 advancing the same.

17. In a system of telegraphy, a character containing vertical and transverse elements for printing a number of the letters of an alphabet, and another character containing a 45 transverse element which coacts with the first-mentioned character in printing the remainder of the letters of the alphabet, said characters being arranged close together so that the marks made by one will join or 50 nearly join the mark made by the other.

18. In a system of telegraphy, a character containing vertical and transverse elements for printing a number of the letters of an alphabet, another character containing a transverse element which coacts with the first-mentioned character in printing the remainder of the letters of the alphabet, said characters being arranged close together so that the marks made by one will join or nearly join 60 the mark made by the other, and means for controlling said characters.

19. In a system of telegraphy, a character containing vertical and transverse elements for printing a number of the letters of an alphabet, another character containing a trans-

verse element which coacts with the first-mentioned character in printing the remainder of the letters of the alphabet, said characters being arranged close together so that the marks made by one will join or 70 nearly join the mark made by the other, and means for electrically controlling said characters.

20. In a system of telegraphy, means for printing an alphabet of separate letters each 75 of which has connected elements, said means consisting of two characters embracing all of said elements, substantially as described.

21. In a system of telegraphy, means for printing an alphabet of separate letters each 80 of which has connected elements, said means consisting of two characters embracing all of said elements, and means for moving the characters so they will print the letters in alinement.

22. In a system of telegraphy, a stylus 85 consisting of two coacting characters containing vertical and transverse elements for printing all of the letters of an alphabet in separate form, and a transmitter in circuit with said stylus whereby impulses of varying duration are transmitted to the characters.

23. In a system of telegraphy, a reciprocatory stylus consisting of two characters adapted to print while moving in either direction, said characters embracing all of the 95 elements for printing an alphabet composed of separate letters.

24. In a system of telegraphy, a reciprocatory stylus consisting of two characters 100 adapted to print upon paper while moving in either direction, said characters embracing all of the elements of an alphabet, and means for lifting the characters from the paper when they reach the end of each stroke.

25. In a system of telegraphy, a stylus 105 consisting of two coacting characters containing vertical and transverse elements for printing all of the letters of an alphabet in separate form, a transmitter in circuit with said stylus whereby impulses of varying duration are transmitted to the characters, and means for synchronizing the movements of the stylus and the transmitter at the end of each stroke.

26. In a system of telegraphy, a reciprocatory stylus consisting of two characters adapted to print upon paper while moving in either direction, said characters embracing all of the elements of an alphabet, and inclined arms for lifting the characters from 110 the paper when they reach the end of each stroke.

27. In a system of telegraphy, a receiver 115 consisting of feed-rollers for feeding paper step by step, a chemical bath wherewith the paper is treated, and a reciprocatory stylus for printing separate letters of an alphabet upon the paper, said stylus consisting of a character containing vertical and transverse elements for printing a number of the letters 120 125 130

of the alphabet, and a character which coacts with the first-mentioned character in printing the remainder of the letters of the alphabet, said characters being arranged close together so that the marks made by one will join or nearly join the marks made by the other.

In testimony whereof I affix my signature, in the presence of two witnesses.

ROBERT L. DEAN.
